UNITED STATES PATENT OFFICE.

REGNAR KIDDE, OF CHAPPAQUA, NEW YORK.

DESIGN FOR AN AUTOMOBILE HEATER.

Application filed June 2, 1926. Serial No. 17,914. Term of patent 14 years,

To all whom it may concern:

Be it known that I, REGNAR KIDDE, a citizen of the United States, and resident of Chappaqua, in the State of New York, Westchester county, and whose post-office address is post-office box 254, Chappaqua Road, Chappaqua, New York, have invented a new, original, and ornamental Design for Automobile Heaters, of which the following is a specification, reference being had to the accompanying drawing, forming part thereof.

The figure is a perspective view of an automobile heater, showing my new design.

I claim:

The ornamental design for an automobile heater as shown.

REGNAR KIDDE.
